US00D952947S

(12) **United States Design Patent** (10) Patent No.: **US D952,947 S**
(45) Date of Patent: **** May 24, 2022**

(54) **COMB FOR TRIMMER**

(71) Applicant: **KONINKLIJKE PHILIPS N.V.**,
Eindhoven (NL)

(72) Inventors: **Lacides Manuel Marquez**, Almere
Buiten (NL); **Pascal Kuijpers**,
Amsterdam (NL); **Maren Baake**,
Amsterdam (NL); **Ulrike Herremans**,
Eindhoven (NL)

(73) Assignee: **KONINKLIJKE PHILIPS N.V.**,
Eindhoven (NL)

(**) Term: **15 Years**

(21) Appl. No.: **29/711,429**

(22) Filed: **Oct. 31, 2019**

(30) **Foreign Application Priority Data**

May 2, 2019 (EM) 006414132-0002

(51) LOC (13) Cl. **28-03**

(52) U.S. Cl.

USPC **D28/54**

(58) **Field of Classification Search**

USPC **D28/54**

CPC .. B26B 19/3826; B26B 19/3886; B26B 19/20

Primary Examiner — Jennifer Rivard

(57) **CLAIM**

The ornamental design for a comb for trimmer, as shown and described.

DESCRIPTION

FIG. 1 is a perspective view showing our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 4 Drawing Sheets
